(No Model.)

H. R. ALLEN.

MOWING MACHINE.

No. 268,377.

Patented Dec. 5, 1882.

WITNESSES.

Jacob W. Looper

Chas. L. Thurber.

INVENTOR.

Horace R. Allen,

C. Bradford

ATTORNEY.

UNITED STATES PATENT OFFICE.

HORACE R. ALLEN, OF INDIANAPOLIS, INDIANA.

MOWING-MACHINE.

SPECIFICATION forming part of Letters Patent No. 268,377, dated December 5, 1882.

Application filed December 27, 1881. (No model.)

To all whom it may concern:

Be it known that I, HORACE R. ALLEN, of the city of Indianapolis, county of Marion, and State of Indiana, have invented certain new and useful Improvements in Mowing-Machines, 5 of which the following is a specification.

The object of my said invention is to improve that part of the mechanism of mowing-machines which is immediately connected with the cutter-bar and finger-bar thereof, whereby the cutter-bar may be driven more accurately and steadily than in most other machines, thus requiring less power, and its cutting portion may be more conveniently detached for the purpose of sharpening, &c., and whereby the finger-bar, and with it said cutter-bar, shall be adapted to more accurate adjustment and more convenient handling; and it consists in the construction and arrangement of parts hereinafter particularly described and claimed.

Referring to the accompanying drawings, which are made a part hereof, and on which similar letters of reference indicate similar parts, Figure 1 is a top or plan view of a machine embodying my invention; Fig. 2, a vertical section looking toward the center of the machine from the dotted line $x x$; Fig. 3, a similar view to Fig. 2, except that a bar, instead of a pipe, is used to support the driving-shaft of the cutter-bar; Fig. 4, a section on an enlarged scale of the gear-case and driving-gears, taken on the line of said driving-shaft; Fig. 5, a vertical section of the lower end of said driving-shaft and connecting parts on the dotted line $y y$; Fig. 6, a transverse section of the head of the driving-shaft and accompanying parts on the dotted line $z z$, and Fig. 7 a view showing a construction which may be employed instead of that shown in Fig. 6.

In said drawings, the portions marked $A A'$ represent the wheels of the machine; B , the axle thereto; C , the frame-work or inclosing casing thereof; D , the tongue or pole; E , the seat; $F G H I J K$, a system of gear-wheels; L , a shaft running from the concluding wheel of said set to the cutter-bar; M , an eccentric on said shaft; N , said cutter-bar, having a yoke, N' , in which is a slot or opening, in which said eccentric revolves, and thus moves said bar; O , the finger-bar; P , the shoe; Q , a bar or pipe connecting the casing on the axle and

said shoe, and R a brace running from a point on said axle or the frame-work to a point on said bar near said shoe.

The wheels, axle, frame-work or casing, tongue, and seat are not in themselves peculiar, and can be readily understood from the drawings and the foregoing brief description.

In the system of gears shown that marked F is internally toothed, and is fixedly secured 60 inside the casing C . Those marked G and H are mounted, by means of short pivot-shafts g and h , upon the loosely-mounted wheel I upon the axle, and mesh into both the internal gear, F , and the smaller or pinion portion of the double gear J . The larger or bevel portion of said wheel J meshes into the pinion K on the shaft L . When the clutch I' is not engaged with the hub of the wheel I (see Fig. 4) the gears remain motionless, and the shaft L and cutting 70 machinery are therefore out of operation. When, however, the clutch I' (which moves longitudinally along the axle, and is held from turning by a spline thereon) is thrown into engagement with the hub of the wheel I , said wheel is 75 thereby put in motion, and with it the wheels G and H , and also the wheel J , by reason of the engagement of said wheels G and H with the internal gear, F . This arrangement gives said wheel J a rapid rate of speed, and thus 80 also drives the wheel K and shaft L very fast, as is necessary in mechanism for this purpose.

The shaft L and eccentric M are ordinary forms of such devices. The eccentric may be replaced with a crank, if desired, as shown in 85 Fig. 7. This latter may be found even preferable to the former, as an anti-friction roller may be placed upon the crank-pin, if desired, which cannot be done to advantage on an eccentric.

The cutter-bar N has the yoke N' attached to or forming a part thereof, which, while not a new form of mechanism, is, as I believe, new in this connection. The eccentric M fits into the slot or opening therein, and as it revolves, 95 by reason of its form, forces the yoke and the cutter-bar, of which said yoke forms a part, back and forth. The cutter-bar is provided with bearing portions n^2 n^3 upon both sides of the yoke, and this, in addition to yoke attachment just described, gives a very steady movement to said bar, and prevents the jerking and 100

consequent loss of power and extra wear which occurs when the ordinary pitman-connection is employed.

A very convenient means of uncoupling the cutter-bar for the purpose of removing it to sharpen the knives, and for other purposes, consists in forming right-and-left-handed screw-threads upon the two parts thereof where they come together, and connecting them by a right-and-left-handed nut, N^2 , as shown. A leather or other compressible washer (indicated by the heavy black line between the ends) should be inserted between said ends. A coupling-joint may be substituted for one of the screw-threads, as shown in Fig. 7.

The lower end of the pipe Q has a casting, Q' , which is mounted thereon, and is capable of a rotary movement around said pipe. The shoe P , and with it the heel of the finger-bar, is connected to this casting by the shoe being pivoted on the trunnions q q' on the sides of said casting by means of the bearing-block p or some similar device. This last-described attachment permits the cutter-bar to be rotated somewhat when necessary to bring the knives into the proper cutting position, while the rotary movement, of which the casting Q' is capable, around the pipe Q permits the whole finger-bar and its attachments to be raised to a vertical position, or such position as is desired, by any of the means adapted for that purpose, none of which are thought necessary to be shown or described here.

The operation of my said invention is as follows: The wheels, axle, and gears being put in motion in the ordinary manner by drawing the machine, the shaft L is also rotated, and by means of the eccentric M , secured thereon, and the vertical slot in the yoke connected to the cutter-bar, drives said cutter-bar back and forth. When it is desired to alter the cut of the knives the inclination thereof can be va-

ried by slightly rotating the finger-bar and shoe on the trunnions q q' by means of the rod P' and lever P^2 , or otherwise. When it is desired to raise the finger-bar it can be done by rotating the casting Q' , on which said finger-bar and the shoe are mounted, on the pipe Q . When it is desired to remove the cutter-bar it can be done by simply unscrewing the right-and-left-hand-threaded nut N^2 , which connects the back or bar to which the cutting sections or knives are attached to the portion in which is the yoke N' , thus permitting the cutter-bar to be drawn entirely out from the outer end of the finger-bar.

Having thus fully described my said invention, what I claim as new, and desire to secure by Letters Patent, is—

1. The combination, in a mowing-machine, of a shaft, L , which connects the cutter-bar to the driving-gear on the axle, and which is provided with an eccentric or crank upon its end, a casing, Q' , at the lower end of and surrounding said shaft, provided with two bearings, q q' , one on each side of said shaft, and the cutter-bar N , mounted and moving in said bearings, and provided with a yoke, N' , in which the crank or eccentric revolves, all substantially as set forth.

2. In a mowing-machine, the combination of the shaft L , the arm or tube Q , having attachment Q' mounted and adapted to turn thereon, and also having trunnions on which the shoe is mounted and adapted to turn, and the shoe, all substantially as shown and described, and for the purposes specified.

In witness whereof I have hereunto set my hand and seal, at Indianapolis, Indiana, this 19th day of December, A. D. 1881.

HORACE R. ALLEN. [L. S.]

In presence of—

CHAS. L. THURBER,
C. BRADFORD.
